United States Patent Office

Des. 205,658

Patented Sept. 6, 1966

205,658

CHAIR

Walter Muller, Lerchenbergstrasse 123, Erlenbach,
Zurich, Switzerland

Filed June 11, 1965, Ser. No. 85,692

Claims priority, application Switzerland Feb. 3, 1965

Term of patent 14 years

(Cl. D15—1)

Fig. 2

Fig. 1

Fig. 5

Fig. 4

Fig. 3

The side of the chair opposite that shown in FIGURE 2 is a mirror image of the depicted side of FIGURE 2.

I claim:

The ornamental design for a chair, substantially as shown and described.
